DESIGN FOR SPECTACLES

Albert F. Doebrich, Buffalo, N. Y.

Application May 29, 1940, Serial No. 92,692

Term of patent 14 years

To all whom it may concern:

Be it known that I, Albert F. Doebrich, a citizen of the United States, residing at Buffalo, in the county of Erie and State of New York, have invented a new, original, and ornamental Design for Spectacles, of which the following is a specification, reference being had to the accompanying drawing forming part thereof.

In the accompanying drawing:

Fig. 1 is a perspective view of the spectacles embodying my design viewed from the rear thereof.

Fig. 2 is a front elevation of the same.

Fig. 3 is a side elevation of the same viewed from the right of Fig. 2.

I claim:

The ornamental design for spectacles, as shown.

ALBERT F. DOEBRICH.
